COKING RETORT OVEN

Joseph Becker, Pittsburgh, Pa., assignor, by
means assignments, to Koppers Company, a
corporation of Delaware

Application January 19, 1935, Serial No. 2,564
In Great Britain October 25, 1933

12 Claims. (Cl. 202—151)

The invention relates in general to improvements in coking retort ovens of the type of the well known cross-over ovens exemplified in the Joseph Becker Patent No. 1,374,546 granted April 5 12, 1921, and more particularly the invention relates to improvements in that type of coke ovens exemplified in the Joseph Becker Patent No. 1,904,191.

The present application is a continuation in 10 part of my co-pending application Serial No. 587,541, filed January 19, 1932, now Patent No. 2,015,657 issued October 1, 1935, and also a continuation in part of my co-pending application Serial No. 639,448, filed October 25, 1932, now Patent No. 2,019,843, issued November 5, 1935.

The invention concerns the provision of improvements in the type of ovens shown in my aforesaid Patent No. 1,904,191; and main objects of the invention are: to reduce resistance in the 20 gas circuits around the coking-chambers, the circuits through which the combustion media and combustion products flow from the base of flame-flues on one side of a coking-chamber upwards and over the coking-chamber and down to the base of the down-flooring flues on the other side of the coking-chamber, and at the same time providing exact regulation for the combustion media where they enter the up-burning flame-flues; such reducing of resistance, while maintaining 25 such exact regulation, having the effect of diminishing pressure differences all along the course of such gas flow and permitting the flow to be effected both under lower pressures and stack-draft and also with consequent lower pressure differentials between the gases in the combustion flues and the gases in the contiguous coking-chamber or chambers, thereby also minimizing any tendency to leakage from the flues into the coking-chamber or elsewhere; the provision of a 30 vertical combustion flue construction in the heating walls and the communicable connection of the vertical flues of the heating walls with the vertical flues in others of the heating walls by freely flowing horizontal and cross-over flues, together with regulation means for regulation of 35 the gas and air for the vertical combustion flues at the bottoms of the vertical flues, so as to remove resistance to the passage of gas through the vertical flues, horizontal flues and cross-over flues. In ovens of the type in which the present invention is an improvement, the burning gases in the upflow vertical flues have been regulated by means of the restricted ports and sliding bricks therefor at the tops of the vertical flues. The 40 restricted top ports and the adjustment of the

sliding bricks restricted the cross-sectional area of the vertical flues to less than the maximum aggregate cross-sectional area of the air and gas inlet ports to the vertical flues, producing a gas throttling effect. The throttling of the gases 5 causes increased differences in pressure between the upper parts of the vertical flues operable for upflow and those following portions of the other flues that operate concurrently for off-flow of waste gas toward the regenerators and the stack; such differences in pressure being much steeper and higher than they would be were such restrictions omitted. Further such throttling may slow up the flow of gas and result in building 10 up of gas pressures slightly greater than the gas 15 pressure in the adjoining coking chambers, especially alongside the upper parts of the coking-chambers where some of the waste gas from the vertical flues might leak into the coking-chamber and flow off with the distillate gas issuing from 20 the coking chambers.

The present invention overcomes such pressure difficulties while still furnishing the required regulation, by providing for graduated control 25 through the relatively small air and gas inlet ports in the bottoms of the vertical flues where all throttling of the gas and air will occur at or below the bottoms of the vertical flues, and by providing the vertical flues at their tops with 30 openings that are relatively very large in comparison to the effective aggregate cross-sectional area of the gas and air inlets to the vertical flues, so that the vertical flues are practically free of 35 constrictions at their upper parts that would build up pressures. In the present construction 40 the outlets from the upper parts of the vertical flues do not present the back pressure conditions which obtain when the control is at the top rather than the bottoms of the vertical flues. In this manner the up-burning flues are operable 45 with smaller gas pressure, the differences in pressure along the path of flow from the inlet of an up-burning vertical flue to the regenerator outlet of the down-burning vertical flue are less sharp; and the oven battery as a whole is capable of 50 being operated under lesser stack draft. The invention has for further objects such other operative and structural advantages or results as may be found to obtain in the structures and operation hereinafter described and claimed.

In the accompanying drawings, forming a part 55 of the specification and showing for purposes of exemplification certain preferred forms and manner in which the invention may be embodied and practiced, but without limiting the claimed invention.

tion specifically to such illustrative instance or instances:

Fig. 8 is a perspective view of one of the sliding bricks;

Fig. 9 is a fragmentary vertical view similar to Fig. 1 of an oven or battery of the underjet type embodying the present invention;

Fig. 10 is a fragmentary composite vertical sectional view, similar to Fig. 2, taken on the lines 40 C—C and D—D of Fig. 9.

Like reference numerals indicate like parts in the several views.

In the embodiments illustrated in the drawings, the invention is incorporated in a combination coke oven battery, that is, a battery having provision for being fired alternatively with an extraneously derived relatively lean gas, such as producer gas, or with a relatively rich gas such as coke oven gas. For convenience, the present description will be confined to the present 45 illustrated embodiment of the invention in such a combination oven battery; features of the invention may be applied to other structures, for example, to ordinary so-called "coke-ovens" fired 50 with coke-oven gas, or ordinary so-called "gas ovens" fired with producer gas; hence, the invention is not confined in its scope to the combination oven or to the specific use and specific embodiment herein described as an illustrative 55 example.

As the present improvements are useful with various types of cross-over ovens and as the details of such improved ovens may be readily understood by reference to my aforesaid patents 60 and copending applications which are made a part hereof, a brief description of the various parts of the oven battery that are concerned with the present improvements will suffice for an understanding of the same.

The coking retort oven or oven-battery comprises a series of horizontal coking-chambers 10 and intermediate heating-walls 12 therefor and side-by-side therewith, and series of side-by-side cross-regenerators 13, 14 below and paralleling 65 the series of coking-chambers and heating-walls,

together with the communications between said heating-walls and regenerators and the further gas conduits and supporting walls and other structures shown. The heating-walls comprise vertical heating-flues 15 disposed in sets, one set 5

in each heating-wall, the sets in pairs of mutually adjacent heating-walls being mutually connected by cross-over conduits 16 through which the hot combustion-products or waste-heat gases from the up-flow or burning set of heating-flues 10 in one heating-wall flow over to the down-flow set of heating-flues in the other heating-wall of the pair, the flow being reversed and the up-flow set becoming the down-flow set and vice versa upon the reversal of the regenerative system. 15

The lower ends of the cross-over conduits 16 port into horizontal passages 17 that communicably join the top outlets 18 of the heating flues in the heating-walls. The set of heating-flues in each heating-wall, all of which flow in one direction, either upward or downward, at any one time, are disposed in groups of four heating-flues 20 each except at each end of each wall where the end groups are in pairs, the several heating-flues in each group being separated from each other by vertical partitions 19 transverse of the heating-wall, the partitions within each group stopping somewhat short of the top of the heating-wall to provide the above-mentioned communicating passages 17. The flow from or to 25 the heating-flues in each group traverses directly the cross-over conduit 16 that is above the middle partition 19 in such group, and the top of said middle partition is flared, at 22, beneath the adjacent port of the cross-over conduit, to promote 30 equality of flow to or from the middle heating-flues of the group and to or from those heating-flues of the same group that are farther from said cross-over conduit. In the said set of heating-flues, comprised in the heating-wall, there 35 are about eight of the adjacent groups and a corresponding number of cross-over conduits 16 respectively serving said groups and the corresponding groups in the set of heating-flues comprised in the adjacent heating-wall of the pair. 40

The tops of the heating-flues of each heating-wall are accessible through the usual inspection holes 23 extending to the top of the oven or battery.

The horizontal coking-chambers 10, intermediate the heating-walls, are of greater height than the heating-walls and have their opposite ends closed as usually by removable doors 24, and are tapered laterally about two inches from the pusher end 10^a toward the coke end 10^b, the door 55 on the pusher-side end of the chamber being as usually constructed with an opening at its upper part through which the leveler bar of the pusher machine may be entered to level off and determine the height of the top of the coal charge 26, which enters through the top charging openings 32 and which is commonly somewhat higher than the tops of the aforesaid heating flues and horizontal gas flow spaces 17, so that, upon shrinkage of the coal in coking, the top of the coked 60 charge will still be a little above the tops of the heating-flues and horizontal gas flow spaces 17, thereby insuring a relatively cool coke-charge top immediately below the gas-collecting crown space 27' of the coking-chamber, and thereby 65 protecting from decomposition the distillation gases that collect in such crown space and flow off from the coking-chamber through the ascension pipes 54 that communicably connect the ends of the coking-chamber with the gas-collect- 70 75

ing mains 11 mounted along the pusher-side and coke-side respectively of the battery.

The aforesaid cross-regenerators, below and paralleling the series of coking-chambers and heating-walls, are disposed in groups of four, each group having two middle gas-regenerators 13, 13, flanked by two air-regenerators 14, 14. The gas-regenerators 13, 13 are adapted for preheating poor or weak gas, such as producer gas or blast furnace gas, but are also adapted for preheating air when the ovens are being fired with strong gas, such as their own distillation gases which do not require regenerative preheating. The air-regenerators 14 are adapted for preheating air and in each group they flank the middle gas-regenerators 13, 13 which are thereby isolated from the regenerators of adjacent groups that are simultaneously operating for down-flow or outflow of waste gases, such isolating of the gas-regenerators serving to eliminate possibilities of leakage of gas into the countercurrent flow of waste gases under lower pressure in said adjacent regenerator groups. At any given time, alternate groups of regenerators operate for up-flow of gas and air and the intermediate groups for down-flow of waste gases, these relations being reversed at each period of reversal of the regenerative system (as set forth in, for instance, my Patents No. 1,678,802 and No. 1,904,191). Each pair of gas-regenerators 13 communicates through two ducts 27, 27 at their tops with heating-flues 15 in heating-walls that are on respectively opposite sides of the coking chamber that is directly above such gas-regenerators; and the two air-regenerators 14 that flank said gas-regenerators each communicate respectively, through ducts 28, with the heating-flues in one of said two heating-walls that are both in communication with said gas-regenerators. Such two heating-walls operate simultaneously in the same direction in respect of each other and respectively belong to two adjacent pairs of the pairs of heating-walls that are connected by cross-over conduits 16 in the manner before described. The groups of regenerators are separated from each other by the oven supporting pillar-walls 29 that are respectively located directly below those coking-chambers which are within the paired heating-walls that are connected by the cross-over conduits 16 as above mentioned. In each group the gas and air regenerators are separated from each other by the oven supporting pillar-walls 30 that are respectively located substantially below the two heating-walls that are fed by and receive waste gas from the regenerators of said group. These pillar-walls 30 within each regenerator group are of somewhat thicker structure than the pillar-walls 29 between the adjacent groups of regenerators. The above-described regenerators are in two series lengthwise of the battery, one series for the pusher-side half of the battery and the other series for the coke-side half of the battery, the cross-regenerators of the one series abutting end for end, along the lengthwise middle of the battery, with the corresponding cross-regenerators of the other series and being separated therefrom by the median longitudinal partition wall 31 that extends longitudinally along the middle of the battery transversely under the middle of the series of coking-chambers and heating-walls comprised in the super-structure above the regenerators. The abutting gas-regenerators in the pusher-side series and coke-side series respectively are fed with gas from the usual gas-mains that

extend along the pusher-side and coke-side respectively of the battery. Each pair of abutting gas-regenerators has a sole-channel 34 extending lengthwise of it under the checkerbrick. All of the sole-channels are provided in their outer ends with communications 36 for connection with the usual (but not shown) air-boxes, all of which are provided with air inlet valves and also communicate through connections with an adjacent waste gas tunnel, one such tunnel extending 10 along the outside of the sub-structures on either side of the battery. Air-boxes, as usually, are provided for the gas regenerators, these air-boxes having valved communication, through connections, with the respective gas-mains on opposite 15 sides of the battery, that supply gas for the gas-regenerators; and the air inlet valves for these air-boxes are at all times kept closed when the battery is being fired with gas from said gas-mains that feed the gas-regenerators. The usual 20 reversal mechanisms are provided for operating the valves of the air and gas and waste gas connections just above mentioned, which control the inflow and outflow to and from the regenerators of the battery. When the battery is being fired 25 with strong gas, such as its own gases of distillation, which does not require regenerative preheating but has a large air requirement, all of the connections of the regenerators 13 to the gas-mains are kept closed, and all of their air-boxes 30 are employed for supplying air to and withdrawing waste gases from all of the regenerators of the battery, thus providing an increased supply of regeneratively preheated air by utilizing for air not only the air-regenerators 14 but also the gas-regenerators 13 that would otherwise be employed 35 for preheating extraneously derived weak or poor gas, such as producer gas or blast furnace gas.

For alternatively firing the battery with rich gas, such as its own gases of distillation, the 40 base of each heating-flue is provided with a gas-conduit 41 that extends directly downward to a rich-gas conduit 40 in the capital of pillar-walls 30 (Figs. 1 to 8), and in the modification shown in Figs. 9 and 10, down through the 45 foundation-mat 42 that supports the regenerators. In the latter instance each such conduit is provided at its lower exposed end with an individual hand-valve 43 that is accessible below the battery and by which the gas flow for the 50 conduit may be individually regulated by the operator. Further individual pipe-connections 44 connect each conduit with a branch-header 45 that is in turn connected by a pipe 46 with a gas-main 47 that supplies gas to the battery 55 from some reservoir-source in which the gases of distillation of the same battery, or of like batteries in the same plant, are collected and stored. There are two such gas-mains 47 extending longitudinally under the battery, one 60 under its pusher-side half and one under its coke-side half; and there is a branch-header 45 for each such half of each heating-wall in the battery. The automatic reversing mechanism of the battery is connected with the lever-arms 48 65 of the valves 49 in the pipe connection 46 between each branch-header pipe 45 and its corresponding gas-main 47. And during alternate reversal periods the supply to alternate pairs 50 of these branch-headers are respectively opened 70 and shut. The gas-conduits 41, individual to the heating-flues, are placed inside the supporting walls 30 that are within the respective regenerator groups before described, and in each instance feed gas to the respective heating-walls that 75

are fed by the same regenerator group, so that whenever gas is flowing upward through a gas-conduit 41 there is no countercurrent flow in the regenerators on either side of the wall in which that conduit is placed, but the flow through the regenerators on both sides of such wall is then in the same direction, that is, toward the heating-flues, as the flow in the conduit itself, and so pressure differences are minimized on either side of such conduit and there is a corresponding minimizing of the possibility of leakage between the gas-conduit and the contiguous regenerators that are simultaneously filled with up-flowing air. When the same regenerator group is operated for waste gas outflow, the gas conduits 41 in the walls 30 within such group have already been shut off by the reversing mechanism and there is no gas flow through them that can be affected by any possibility of leakage through the walls that incase the gas conduits.

The checkerwork in the regenerators is subdivided by vertical transverse curtain-walls 52 to promote equality of distribution of flow.

In accordance with the present improvements, the regulation of gas flow is effected from the bottoms of the vertical flues 15 instead of at the tops of the same as heretofore; and the vertical flues 15, horizontal gas flow spaces 17, cross-over flues 16, and communications 18 of the vertical flues 15 with the horizontal gas flow spaces or horizontal flow duct means 17, are made of such large effective cross-sectional area that the gas is not subjected to pressure building or to gas throttling impedance during its course of flow from the gas and air inlets 27, 28 of each flue operable for up-flow combustion to the regenerator outlets 27, 28 of the combustion flues serving at the same time to exhaust the waste gases of combustion from the up-burning flues 15.

To this end a pair of sliding bricks 33 are slidably mounted in the bottoms of each vertical flue for individually regulating the effective cross-sectional area of the regenerator ports 27, 28 that open into the vertical flues. These bricks 33 have side flanges 37 which are guided by ledges 38 but ride on the seat 38' for said bricks 33. The ports 27, 28 merge in a common outlet for which the pair of bricks 33 and ledges 38 additionally serve as limiting walls. The rich gas conduits 41 for each flue 15 are each provided with removable nozzles 39 for interchange to vary the effective outlet area of the rich gas ducts. The ports 27, 28, and their bricks 33 are designed to determine the delivery of the required quantities of regeneratively preheated air and weak gas at the required velocity for each flue 15, and also for conjoint supply of preheated air or separate and simultaneous supply of preheated air and an inert gas, when the flues are fired with unpreheated rich gas from conduits 41. In the structure illustrated in Figs. 1 to 8 regulation of the quantities or velocity of flow of gas through the flues is effected by adjusting the bricks 33 relative to the outlet of regenerator ports 27, 28 and (if necessary) by interchange of nozzles 39, by means of long rods inserted through the access openings 23 at the top of the oven. Usually it suffices merely to regulate the sliding bricks 33 for ports 27 and 28, and interchange of the nozzles 39 is thereby rendered unnecessary. In event that regulation is desired for the conduits 41 this may be done, in a structure such as shown in Figs. 9 and 10, from beneath the battery by manipulation of the valves 43 and only the slid-

ing bricks 33 adjusted through the access passageways 23 at the top of the battery. In this manner all throttling and pressure increase of the gas occasioned by regulation occurs below the bottoms of the vertical flues 15, at the top of the regenerators, where such throttling or pressure increase is minimized because of the fact that the regenerators act as a common reservoir for a constant source of gas or air and have a substantial free space above the tops of the checkerbrick to equalize pressure as shown in Fig. 3.

Advantageously, then, the effective cross-sectional area of the cross-over flues 16, horizontal gas flow space 17 and the communications 18 of the vertical flues 15 at their upper parts with the horizontal gas flow space 17 are made sufficiently large that they have no material effect upon the gas flow and in this way the gas flow through the flues occurs with lesser differences in pressures from inlet to outlet and less draft is required for gas flow.

For uniform heating of the coal charge in the adjoining chambers it is necessary to supply more heat progressively towards the coke-side from the pusher-side, due to the tapering of the oven to accommodate pushing of the finished coke charges from the coking-chambers 10. To this end the flues 15 in each heating-wall are arranged in six intermediate groups of four flues 15, one end group of two coke-side flues, and one end group of two pusher-side flues 15. As shown in Fig. 5, the dimension "X" of the flues 15, lengthwise of the heating-wall, is the same for all flues, but the flue width "Y" (Fig. 5) is, cross-wise of the heating-wall, largest on the pusher-side 10^a and decreases uniformly towards the coke-side 10^b to the smallest width as indicated by Y'.

The maximum areas of the common outlets for the regenerator ports 27, 28, except for the two end groups of flues 15, are approximately the same, about 3" by 5", and these are graduated from the pusher-side 10^a toward the coke-side 10^b by the normal setting of the bricks 33, to provide variably greater ports, varying from 12 sq. in. to 15 sq. in., for supplying relatively more air and gas to the flues 15 toward the coke-side, to compensate for the greater heating required due to the tapering of the coal charge. It is not necessary, however, to provide successively greater inlet areas for successive flues but only groups of flues as shown in Fig. 5, since the increase in width of the charge in the chamber 10, from one flue 15 to the next flue 15, is not sufficiently great for such graduation. Graduation of the ports in groups, as indicated in Fig. 5 and the following table of areas, is preferred.

Table of combined air-and-gas regenerator ports

Port No.	Width Inch	Length Inches	Area Sq. inches
P1 and P2	2	6	24.00
P3 to P6	3	5	15.00
P7 to P10	3	4.75	14.25
P11 to P14	3	4.5	13.50
P15 to P18	3	4.25	12.75
P19 to P22	3	4.125	12.375
P23 to P26	3	4	12.00
P27 and P28	4	5	20.00

As indicated in Fig. 5 and in the table of areas, the first two coke-side ports and the first two pusher-side inlet ports are of relatively greater

area, with the first two coke-side ports greater than the first two pusher-side ports. This is to compensate for the greater radiation of heat through the doors and walls at the ends of the 5 chambers 10, and the relatively thicker coal mass at the extreme coke end 10^b of the chambers 10 than the pusher end 10^a. The conduits 41 do not exceed 2 inches in diameter and this area is always less, usually 1 inch, due to the restriction 10 of the nozzles 39 whose ports average about 1 square inch as compared with the areas of 12 to 15 and 20 to 24 square inches of the above-indicated ports.

Preferably alternate partitions 19 are stopped 15 shorter at their upper ends below the upper ends of the intermediate partitions 19 to provide for a common outlet 18, into the horizontal gas flow space 17, for the pair of flues separated from each other by the alternate partitions, and the 20 tops of the other intermediate partitions are flared as at 22 similarly to the flared tops 22 to cause the gas from the vertical flues of each group which are further from the flared tops 25 22 to have more nearly the same length of travel and flow condition as the gas issuing from the flues alongside the portions having the flared tops 22. Referring to Figs. 1, 4, 9 and 10, the outlets 18' for the end groups of two vertical flues, P1, P2 and P21, P28, are made to have the same 30 cross-sectional area, 9" wide and 23 $\frac{1}{8}$ " long. The outlets 18 for all of the intermediate groups of flues 15 are the same, 9" wide and 15 $\frac{3}{4}$ " long. Such areas are greater than the possible maximum area of the gas and air inlets to the two 35 vertical flues served by the respective outlets 18. It is not necessary to vary the width or length of these outlets 18 due to the fact that they are three or four times larger than the ports at the tops of the vertical flues of the structures 40 of my aforesaid patents so that graduating the size of these outlets 18 from one end of the coking-chamber to the other would have no effect upon the distribution of the gases; in other words, the regulation of the air and gas is done 45 in the ports in the bottoms of the vertical flues, and the ports at the top of the flues are made sufficiently large that they have no material effect upon the gas flow. The horizontal gas flow space is made large enough so that each 50 portion thereof is of large enough effective cross-sectional area to accommodate all the gas flow from the vertical flues 15 served by such portions without increasing the resistance to the flow of the gas.

55 In the present embodiment of the invention the effective cross-sectional area of each part of the horizontal gas flow space or duct means 17 is about 180 sq. in., and the cross-over flues 16 are all about 13 $\frac{3}{4}$ " in one direction marked "U" 60 in Figs. 1 and 9 but in the other direction marked "V" in Figs. 1 and 9 are graduated from the coke-side to the pusher-side as follows: 10 $\frac{1}{2}$ ", 9 $\frac{5}{8}$ ", 9 $\frac{3}{8}$ ", 9 $\frac{1}{8}$ ", 8 $\frac{7}{8}$ ", 8 $\frac{5}{8}$ ", 8 $\frac{3}{8}$ ", the end pusher-side however being 10", due to the larger air and gas inlet area for the pusher end group of two flues 15.

The groups of flues having the same gas and air inlet ports of the same area are preferably separated 70 from each other by partitions 21 in the horizontal gas flow space or duct means 17, and the cross-over flues distributed accordingly, one for each group as shown.

Due to the large areas of the regenerators and 75 the fact that in operation they are substantially

constantly filled with so large volumes of gas or air, graduation of the sole-flues 34 is not essential to uniform distribution; but where exactness in this respect is desired, the sole-flues 34 are tapered so as to narrow towards the middle point 5 36' between the inlets 36 (Fig. 9).

The invention as hereinbefore set forth or exemplified, by said illustrative instances, may be variously embodied and practiced within the scope of the claims hereinafter made. 10

I claim:

1. In a coking retort oven, in combination: a series of side-by-side horizontal coking-chambers and intermediate heating-walls comprising vertical flame-flues for laterally heating said coking-chambers, cross-over ducts for conducting combustion-products from up-burning vertical flues on one side of each coking-chamber to down-flowing vertical flues on the other side of such coking-chamber, horizontal passages over the 20 tops of the vertical flues and each connecting a group of the vertical flues with the cross-over duct centrally connected with the top of such horizontal passage, and inlet means at the base of the vertical flues for controlling the inflow of 25 combustion media into such flues, said inlet means being substantially the sole regulating means for individually regulating the vertical flame flues, the inlet means comprising ports of restricted and graduated cross-sectional areas, 30 and the tops of the vertical flues, the horizontal passages communicating therewith, and the cross-over ducts therefor, each being throughout of greatly larger cross-sectional area than the aggregate of the inlet ports of the vertical flues 35 served by such parts, so that resistance to the initially graduated gas-flow in the circuits around the coking-chambers is diminished and pressure differences are reduced.

2. A coking retort oven as claimed in claim 1 40 and in which the vertical flame-flues of each group communicate in pairs with their respective horizontal passages through a common outlet individual to the pair and centrally disposed with respect to the flues of the pair at their upper 45 parts.

3. A coking retort oven as claimed in claim 1 and in which the vertical flame-flues of each group communicate in pairs with their respective horizontal passages through a common outlet individual to the pair and centrally disposed with respect to the flues of the pair at their upper parts, and in which deflectors are provided, longitudinally of the heating wall, for each flue of a pair only on opposite sides respectively of their common outlet to approximately equalize the length of travel of gas flow through the outlet from the flues of each pair to their cross-over duct. 50 55

4. A coking retort oven as claimed in claim 1 60 and in which the coking-chambers are tapered laterally from the pusher side to the coke side of the oven, and in which separate horizontal passages and cross-over ducts are provided for each group of vertical flame-flues along the heating-walls, and in which the cross-over ducts are of successively increasing effective areas from the pusher side to the coke side of the oven to accommodate successively greater quantities of combustion-products from the successive groups 65 of vertical flame-flues from the pusher side to the coke side of the oven.

5. In a coking retort oven comprising, in combination: a series of side-by-side horizontal coking-chambers and intermediate heating-walls 70

therefor, each of said heating-walls comprising vertical combustion flues having individual air and gas inlet ports in their bottoms and communicating at their upper parts with a horizontal gas flow duct-means adapted to serve the vertical flues in groups, the horizontal gas flow duct-means in each of the heating-walls being communicably connected with a horizontal gas flow duct-means in another of the heating-walls by cross-over duct means extending over an intervening coking-chamber, and regenerators communicating with the combustion flues; the effective cross-sectional area of each of the parts of the cross-over duct-means and horizontal gas flow duct-means, and of the communications of the latter with the tops of the respective vertical flues being throughout substantially greater than the aggregate area of the air and gas inlet ports for the vertical flues served by such parts, to avoid impedances that would augment the pressures of the gas flowing therethrough from the inlet ports; and means for regulating the supply of air and gas from their inlet ports into the vertical flues, the air and gas inlet ports in each heating wall being graduated in cross-sectional area, and said bottom air and gas inlet ports with their regulating means therefor being substantially the sole regulating means for individually regulating the vertical combustion flues.

6. A coke oven as claimed in claim 1 and in which the gas and air inlet ports for each vertical flue comprise two ports for gas and a port for air and in which the regenerators communicate in pairs with each flue, with one regenerator of a pair communicating with an air inlet port and the other regenerator communicating with one of the gas inlet ports to the vertical flue, and in which a conduit for conveying unpreheated rich gas is provided to communicate with the other gas inlet port for the flues, for optional operation of regenerators in communication with gas inlet ports for concurrent inflow of air, and in which the means for regulating the supply of air and gas comprises sliding dampers in the bottoms of the vertical flues for regulating the flow from the regenerator inlet ports, and interchangeable nozzles for the gas inlet ports provided for communication with conduits for conveying rich gas.

7. A coke oven as claimed in claim 5 and in which the regenerators communicate in pairs with each flue, with one regenerator of a pair communicating with an air inlet port and the other regenerator communicating with the gas inlet port to the vertical flue, and in which the means for regulating the supply of air and gas comprises sliding dampers in the bottoms of the vertical flues for regulating the flow from the regenerator inlet ports.

8. A coke oven as claimed in claim 5 and in which the gas and air inlet ports for each vertical flue comprises two ports for gas and a port for air, and in which the regenerators are separated by regenerator walls, and communicate in pairs with each flue with one regenerator of a pair communicating with an air inlet port and the other regenerator communicating with one of the gas inlet ports to the vertical flue, and in which conduits, individual to the respective vertical flues and communicating with the other gas port thereof, extend down through the regenerator walls and terminate in accessible passageways in communication with a conduit for conveying unpreheated rich gas to the flues for optional operation of regenerators in communica-

tion with gas inlet ports for concurrent inflow of air, and in which the means for regulating the supply of air and gas comprises sliding dampers in the bottoms of the vertical flues for regulating flow from the regenerator inlet ports, and regulating valves in the individual conduits in the accessible passageways. 5

9. A coke oven as claimed in claim 5 and in which conduits for conveying unpreheated rich gas are provided to communicate with the gas inlet ports to the vertical flues, and in which the regenerators communicate with the vertical flues through the air inlet ports, and in which the means for regulating the supply of air and gas comprises sliding dampers in the bottoms of the vertical flues for regulating the flow from the regenerator inlet ports, and interchangeable nozzles for the gas inlet ports. 10

10. A coke oven as claimed in claim 5 and in which the regenerators are separated by regenerator walls and communicate through the air inlet ports with the vertical flues, and in which conduits individual to the respective vertical flues and communicating with the gas inlet ports therefor, extend down through the regenerator walls and 15 terminate in accessible passageways in communication with a conduit for conveying unpreheated rich gas to the flues, and in which the means for regulating the supply of air and gas comprises dampers in the bottoms of the vertical flues for regulating the flow from the regenerator inlet ports, and regulating valves in the individual conduits in the accessible passageways. 20

11. In a coking retort oven comprising, in combination: a series of alternate horizontal coking-chambers and intermediate heating-walls therefor arranged side-by-side, each of said coking-chambers being tapered from one horizontal end toward the other and each of said heating-walls comprising vertical combustion flues having 35 individual inlet means for gas and air at their bottoms, flues of each of the heating-walls being communicably connected in groups with the flues of another heating-wall by cross-over ducts crossing over an intervening coking-chamber at 40 spaced intervals therealong, the communication of vertical flues at each end of the cross-overs comprising horizontal gas flow spaces each of which communicably connects a group of vertical flues at their tops with a cross-over and each of which communicates centrally with the latter; the inlet means for the vertical flues being graduated in increasing areas in each wall from the narrower ends of the adjacent coking-chambers towards the wider ends thereof to provide for 45 gradually greater heating and the cross-over ducts for each heating-wall being likewise graduated to accommodate the graduated quantities of combustion-products, the effective cross-sectional area of each of the parts of the cross-over 50 flues, horizontal gas flow spaces, and of the communications of the latter with the vertical flues, being substantially greater than that of the aggregate of the inlet means for the vertical flues served by such parts, to avoid impedance that 55 would augment the pressure of gas flowing through such parts, and regulable means for regulating the inlet means in the bottoms of the vertical flues and said bottom air and gas inlet ports with their regulating means therefor being substantially the sole regulating means for individually regulating the vertical combustion flues. 60

12. A coking retort oven as claimed in claim 1 and in which the vertical flame-flues of each group communicate in pairs with their respective 65

70

horizontal passages through a common outlet individual to the pair and centrally disposed with respect to the flues of a pair at their upper parts, and in which the flues of each such pair are separated from each other by a vertical partition, and in which deflectors are provided, longitudinally of the heating wall, for each flue of a pair, only on opposite sides respectively of their com-

mon outlet to approximately equalize the length of travel of gas flow through the outlet from the flues of each pair to their crossover-duct, and in which the separating partitions between the flues of each pair are stopped short at their upper ends and terminate a distance below the deflectors. 5

JOSEPH BECKER.
